UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

NON-WARNING CHIME-CLOCK.

1,257,024.

Specification of Letters Patent. Patented Feb. 19, 1918.

Application filed October 31, 1917. Serial No. 199,457.

To all whom it may concern:

Be it known that I, WILSON E. PORTER, a citizen of the United States, residing at New Haven, in the county of New Haven, 5 and State of Connecticut, have invented a new and useful Improvement in Non-Warning Chime-Clocks; and I do hereby declare the following, when taken in connection with the accompanying drawings and 10 the characters of reference marked thereon, to be a full, clear, and exact description of the same, and which said drawings constitute part of this application and represent, in—

Figure 1 a view in rear elevation of a 15 chime-clock movement constructed in accordance with my invention.

Fig. 2 a broken plan view thereof, on an enlarged scale, showing the rear movement-plate, the chime-drum driving wheel, the 20 chime count-wheel, the chime guard-wheel and the chime count-hook, of my improved mechanism.

Fig. 3 a detached view in front elevation of the chime-drum driving wheel, the chime 25 count-wheel, the chime guard-wheel, and the chime count-hook, showing the parts at rest.

Fig. 4 a view thereof in inside elevation.

Fig. 5 a view thereof in vertical central section.

Fig. 6 a detached perspective view of the chime count-wheel showing the count-hook 30 in broken lines as being lifted by the rearwardly inclined advancing wall of one of the stop-notches in the wheel.

Fig. 7 a corresponding view of the chime 35 guard-wheel.

My invention relates to an improvement in that class of chime-clocks in which the so called "warning" function is dispensed with 40 and the release of the chime-train by the time-train is effected in one step instead of in two steps as in warning clocks, the object being to provide simple and reliable means for preventing the jamming, and 45 hence the stopping, of the chime-mechanism in case the chime-train thereof is released accidentally, that is to say, in any other way than by the normal action of the time-train.

With these ends in view, my invention 50 consists in a chime-clock having certain details of construction and combinations of parts as will be hereinafter described and pointed out in the claims.

As herein shown, the advancing walls 2 55 of the chime-stop notches 3, 4, 5 and 6 of the

chime count-wheel 7 are rearwardly inclined so as to act as cams upon the finger 8 of the chime count-hook 9 for lifting the same into position to clear the guard-fingers 10, 11, 12 60 and 13 of the chime guard wheel 14 under certain conditions not provided for by the time-train which ordinarily lifts the said hook high enough to clear the said guard-fingers concurrently with its release of the 65 chime-train. The said guard-wheel 14 is mounted so as to turn freely upon the annular shoulder 15 of a hub 16 to the annular shoulder 17 of which the chime count-wheel 7 is staked. The said stop-notches 3, 4, 5 70 and 6 of the count-wheel 7 are separated by peripheral sustaining surfaces or "dwellings" 18, 19, 20 and 21 progressively increasing in length as required for sounding the chime on the quarters and the hour in the usual manner. The rearwardly inclined advancing walls 2 aforesaid, are, in effect, continued outwardly in the forward edges of lifting-fingers 22 virtually forming parts of the "dwellings" 18, 19, 20 and 21 aforesaid. A 80 spring 23 encircling the hub 16, is connected at one end to a screw 24 in the guard-wheel 14 and at its opposite end to the spoke 25 of a chime-drum driving wheel 26 staked upon the rear end of the said hub 16 85 which is mounted upon the projecting rear end of the shaft 28 of the chime-train which comprises, as shown, the said shaft 28, the pinion 29 thereon, a wheel 30 which meshes into the said pinion 29, an arbor 31 which 90 carries the said wheel 30, and a pinion 32 which latter meshes into the main wheel 33 of the chime-train. A stop-pin 34 in the count-wheel 7 projects inwardly through a slot 35 in the guard-wheel 14 and limits the 95 oscillatory movement thereof. The normal tendency of the guard-wheel spring 23 is to hold the same in the position in which its guard-fingers 10, 11, 12 and 13 bridge the respective stop-notches 3, 4, 5 and 6 of the 100 count-wheel 7. The chime-drum driving-wheel 26 meshes into a wheel 36 at the inner end of the chime-drum 37 which is furnished with pins 38 engaging with fingers 39 depending from chime-hammer plates 40 carrying chime-hammer wires 41 mounting hammers 42. The said chime-hammer plates 40 are themselves mounted upon a stud 43 projecting from the rear movement-plate 44. The hammer-plates 40 are also formed with 110 hammer-tails 45 normally resting against a buffer 46. The chime count-hook 9 is mount-

ed upon an arbor 47 periodically operated by the time-train which is of any approved construction, and therefore not shown.

In the ordinary operation of the mechanism described, the count-hook 9 is abruptly lifted every quarter hour through the agency of the time train and concurrently with the releasing of the chime-train thereby. Supposing the finger 8 of the count-hook 9 to be 5 in the stop-notch 3 of the count-wheel 7, as shown in the drawings, the said finger 8 will be lifted as described so as to clear the guard-finger 10 of the guard-wheel 14 the spring 23 of which will quickly assert itself 10 to rock the guard-wheel in the forward direction, whereby its finger 10 will be carried under the finger 8 of the count-hook and bridge the notch 3, while at the same time its fingers 11, 12 and 13 are shot into place 15 to bridge the stop-notches 4, 5 and 6, though to no purpose. The wheels 7 and 14 will now be rotated together by the action of the chime-train, whereby the said finger 8 will ride over the adjacent lifting-finger 22 20 of the count-wheel and drop therefrom upon the "dwell" 18 of the said wheel. As the two wheels are thus rotated together, the advancing edge of the guard-finger 11 engages with the count-hook finger 8, the 25 spring 23 yields and the further rotation of the guard-wheel 14 is stopped. The finger 8 of the count-hook, after a brief interval, drops into the stop-notch 4 and thus permits the arbor 47 to be turned as required 30 for stopping the chime-train. This sequence of events is reproduced on each quarter hour and constitutes the normal operation of the chime-mechanism.

Now in the event of the accidental release 40 of the chime-train instead of its normal release by the time-train, the count-wheel 7 will be started in revolution without preparation therefor by the normal lifting, through the agency of the time-train, of the 45 count-hook 9, the lifting of which in the normal operation of the clock, is concurrent with the starting of the count-wheel. The count-wheel having been accidentally started, as described, the rearwardly inclined advancing wall 2 of the particular count-wheel notch in which the finger 8 of the count-hook happens to be at the moment, will act 50 as a cam to lift the hook sufficiently to permit the complementary finger of the guard-wheel 14 to shoot under it, and thus permit 55 the chime-mechanism to function properly as a chiming-mechanism, but out of order as to time. If the walls 2 of the stop-notches 3, 4, 5 and 6 were not rearwardly inclined 60 as shown and described, the starting of the count-wheel out of time would result in the engagement of the advancing wall of the count-wheel notch with the face of the

count-hook finger and jam or block, and so stop the chime-train beyond the power of 65 the time-train to automatically release it on the next quarter hour. Supposing the chime-mechanism to be thus jammed, it must be released by someone having sufficient knowledge of the construction and operation 70 of chime-clocks to locate the difficulty and remove it. On the other hand, under my invention, in case the chime-mechanism is accidentally started, the count-wheel automatically lifts the count-hook and permits the chiming-mechanism to run through 75 at least one chiming phase, or perhaps more, dependent upon circumstances, but in any event no jamming or blocking can take place. Nothing more serious can therefore 80 happen in case the chiming-mechanism is accidentally started, than the de-synchronizing 85 of the chime and time-trains, and this can be remedied by any user of the clock by manipulating the hands therof.

I claim:—

1. A non-warning chime-clock characterized by having its chime-mechanism constructed and adapted to lift the chime count-hook into position to clear the chime count-wheel in case the chime-mechanism is accidentally started, and therefore at a time when the said count-hook has not been lifted by the action of the time-train to clear the count-wheel preparatory to the starting of 95 the chime-train.

2. In a non-warning chime-clock, the combination with a chime count-wheel having stop-notches separated by peripheral "dwell" and lifting-fingers, the advancing 100 walls and the forward edges of the said stop-notches and lifting-fingers being rearwardly inclined; of a spring-actuated chime guard-wheel located adjacent to the said chime count-wheel and formed with guard-fingers corresponding in position to the respective stop-notches of the chime count-wheel, and a count-wheel hook formed with a finger adapted to co-act with the said count and guard wheels, and normally lifted 105 to clear the same by the time-train concurrently with the operation thereof to release the chime-train, the said count-wheel hook being lifted by the rearwardly inclined advancing walls of the said stop-notches and 110 lifting-fingers in case the chime-train is started otherwise than by the normal action of the time-train, whereby the jamming of 115 the chime-train is avoided.

In testimony whereof, I have signed this 120 specification in the presence of two subscribing witnesses.

WILSON E. PORTER.
